SPRING TOOTH COMBS

Ernest J. Lachance, Leominster, Mass.

Application May 8, 1953, Serial No. 353,835

4 Claims. (Cl. 132—155)

This invention relates to spring tooth combs of the type that have generally boat-shaped teeth with free ends, points or tips, relatively wide center portions, and narrower connected end portions forming the back of the comb, wherein the wider intermediate portions contact or substantially contact each other in order to provide a gripping action on the hair between the individual boat-shaped teeth as well as providing traps for holding the hair adjacent the roots of the teeth at the back of the comb.

The present invention relates to a new and improved comb of this type which is more easily and less expensively manufactured and assembled and which is provided with means for holding the teeth in substantially positive contacting relation, thus improving the gripping action of the teeth and of the comb and at the same time achieving this result by a simplified construction and method of manufacture.

Another object of the invention resides in the provision of a spring tooth comb of the class described made in two parts, one of which comprises the teeth as above described and the connected roots of the teeth forming a comb element which is deeply grooved or recessed between each tooth providing for extremely flexibility thereof, in combination with a recessed elongated trough-like comb back that is curved on an arc, the radius of which is generally normal to the plane of the comb, so that the original connected teeth are curved along the same arc and the individual teeth are forced into firm springy contacting relationship at the intermediate portions thereof.

Other objects and advantages of the invention will appear hereinafter.

Reference is to be had to the accompanying drawings, in which—

Fig. 1 is a view in front elevation of the comb, part 50 being in section;

Fig. 2 is a bottom plan view of the comb;

Fig. 3 is a top plan view of the separate comb blank;

Fig. 4 is a partial view of the tooth blank as originally molded;

Fig. 5 is an enlarged edge view thereof, looking in the direction of the arrow 5 in Fig. 4;

Fig. 6 is a section on line 6—6 of Fig. 3;

Fig. 7 is an enlarged edge view of the finished comb teeth;

Fig. 8 is a view of a blank molded on a different curve; and

Fig. 9 is a composite view illustrating different modifications contemplated in the shape of the grooves between the teeth.

The teeth 10 are shown as in the form of elongated closed rims or the like which when pressed give slightly, so that the teeth are per se springy and are called spring teeth. The rims are generally made boat-shaped as shown and each tooth has a relatively sharp point 12 and a wide intermediate portion at 14. These wide portions preferably touch each other and form spring traps for

2

hair tresses between them so that the comb stays in the hair without being fastened. The teeth are molded and clearly must be molded in spaced relation as shown in Fig. 4.

5 A blank element 16 here connects all of the teeth 10 forming a unit and between the teeth this element is deeply recessed or grooved at 18 rendering the unit resilient and bendable in planes at right angles to each other. That is, the teeth 10 may be now easily moved 10 in together in contacting relation from the spaced relation of Fig. 4, and the entire molded unit can be curved from a flat planar condition into a curve on an arc having a radius normal to the plane of the unit. It is preferred that a combination of these two curvatures be employed to achieve the contacting relation between the teeth as shown in Figs. 1 and 7.

A more rigid comb back 20 in the form of a curved trough having closed ends 22 is used to receive the comb blank element 16 and this device bends the teeth into 20 an arc, see Fig. 7, and exerts pressure on the ends, to tend to close the recesses 18 and to force the teeth into the desired contacting relation.

The blanks of Figs. 3 and 4 are molded, the comb blank elements 16 are merely cemented into the backs 20, and the entire comb is thus easily and inexpensively made.

The comb blank may be originally molded on an arc as shown at 24 in Fig. 8 wherein the teeth 11 do not touch and are radially arranged. The same comb back 30 20 may be used to deform the blank in a different direction, i. e. the blank 24 may be straightened to appear as in Fig. 1, but the curve shown in Figs. 2 and 3 is not necessary although it may of course be used.

Fig. 9 illustrates different formations for the recesses 35 at the ridges of the teeth and shows a keystone shape at 26, a circular closed opening at 28, a circular unclosed opening at 30, and a comb flatwise, coming together at 32. These shapes are intended to be shown when the teeth are in their close contacting position as in Fig. 1.

40 Having thus described my invention and the advantages thereof, I do not wish to be limited to the details herein disclosed, otherwise than as set forth in the claims, but what I claim is:

1. A spring tooth comb comprising a resilient blank, 45 spaced teeth thereon extending from an edge thereof, said blank having recesses in the toothed edge thereof between the teeth, a rigid curved comb back to receive and hold the blank in curved and more rigid condition, said back and said blank being of different curvature so that the blank assumes the shape of the back and the teeth are constrained to touch.

2. A spring tooth comb comprising a resilient elongated blank, spaced spring teeth arranged thereon at one edge thereof in general parallelism, said blank having recesses 55 between the teeth so that the resilience of the blank is increased, a comb back, said blank and back being of different curvatures, said back receiving the blank and holding the same in conformance thereto with the teeth substantially touching.

3. A spring tooth comb comprising a resilient elongated toothed blank having relatively deep recesses therein between the teeth, the recesses extending generally parallel to the teeth and at the same side of the blank, a rigid, curved, trough-like comb back to receive the blank and 65 substantially cover the recesses, the back forcing the blank to bend on a curve having a radius normal to the comb teeth and causing the teeth to touch.

4. A spring tooth comb comprising a resilient elongated toothed blank having relatively deep recesses therein 70 between the teeth, the recesses extending generally parallel to the teeth and at the same side of the blank, a rigid, curved, trough-like comb back to receive the blank

and substantially cover the recesses, the back forcing the blank to bend on a curve having a radius normal to the comb teeth and causing the teeth to touch, the comb back having closed ends bearing on the ends of the comb blank.
